UNITED STATES PATENT OFFICE.

JOHN EDWARD WRIGHT, OF PITTSBURGH, PENNSYLVANIA, ASSIGNOR TO WRIGHT TELEGRAPHIC TYPEWRITER COMPANY, OF NEW YORK, N. Y., A CORPORATION OF DELAWARE.

TRANSMITTER FOR PRINTING-TELEGRAPH SYSTEMS.

1,090,368.

Specification of Letters Patent. Patented Mar. 17, 1914.

Application filed January 22, 1913. Serial No. 743,512.

To all whom it may concern:

Be it known that I, JOHN E. WRIGHT, a citizen of the United States, residing at Pittsburgh, county of Allegheny, and State 5 of Pennsylvania, have invented certain new and useful Improvements in Transmitters for Printing-Telegraph Systems, of which the following is a full, clear, and exact description.

10 The invention, subject of this application for patent, is an improvement in apparatus for use in a printing or equivalent telegraph system in which, by the manipulation of suitable keys, either directly or by means of 15 a perforated tape, signals according to a given code corresponding to letters, figures and other characters, are transmitted over a line to receiving devices by means of which the characters are printed or displayed.

20 In an application filed by me on December 9th, 1912, Serial No. 735,682, I have shown a printing telegraph receiver in which the selection and printing of characters, spacing, paper-feed and such other functions as are involved in the operation of a 25 column-printing telegraph instrument, are effected by means of electromagnetic devices, each having its special function and connected up with a plurality of circuits local 30 to the instrument, in such manner that each particular operation or series of certain operations, results from the completion of a corresponding circuit, or the simultaneous completion of two or more circuits.

35 In order to reduce the number of line or transmission circuits to a minimum, that is a single wire, I employ in connection with such printer an apparatus which I designate as a translator and which is an instrument 40 placed intermediate to the receiver and the line and containing a number of controlling circuits corresponding to those in the receiver, and line controlled circuits as few in number as practical working conditions will 45 permit. By means of current impulses received in one or more of the line controlled circuits in this instrument, that one of a plurality of circuit closers is selected which completes the receiver circuit and prints the

50 character or effects the operation corresponding to the special signal impulse or combination of impulses transmitted over the line. I have made this last named ap-

paratus the subject of an application filed of even date herewith Serial No. 743,511. 55

The improvement upon which my present application is based was designed as that part of the special system involving the two devices above referred to, which transmits current impulses over a single line wire and 60 distributes them in proper time relation to the appropriate line controlled circuits of the translator, and for a more ready understanding of its nature and purpose, it will be described as the transmitter element of that 65 particular system. I do not, however, limit myself to such use, for the apparatus, as will be readily understood by those skilled in the art, is applicable generally to any telegraphic system in which its peculiar func- 70 tions play a necessary or desirable part in the attainment of the ultimate result.

The apparatus may be described in very general terms as composed of two sunflower disks at opposite ends of a transmission line 75 and adapted to operate in unison, but the particular features of novelty which characterize my invention, reside in the means devised and employed for securing the proper synchronization and for otherwise controlling 80 the apparatus in its operation, particularly with reference to the other elements in the system, for which reason I describe the improvements by reference to the accompanying 85 drawings.

Figure 1 is a front view in elevation of that part of the apparatus which is used at the transmitting station. Fig. 2 is a vertical section on line *a*—*a*, of Fig. 1, viewed from the left. Fig. 3 is a similar section on line *b*—*b* of Fig. 1. Fig. 4 is a broken section on line *c*—*c* of Fig. 1, viewed from the right. Fig. 5 is a section on line *e*—*e* of the same figure, viewed from the left. Fig. 6 is a sectional detail on line *d*—*d* of Fig. 1. 95 Fig. 7 is a side view in elevation of an attachment shown at the extreme left of Fig. 1. Fig. 8 is a top plan view of the device shown in Fig. 1. Fig. 9 is a front view in elevation of that part of the apparatus 100 which is used at the receiving station. Fig. 10 is a diagram of circuit connections.

Referring to Figs. 1 to 7 which illustrate sending portions of the apparatus, 1 represents a bed plate supported by legs 2 upon 105 which all the parts are secured. On the

upper side of the base plate 1 are two standards 3 affording bearings for a shaft 4, carrying a loosely mounted sleeve 7 integral with a gear wheel 5 which latter meshes with a pinion mounted in a standard fixed in the base plate, and through which power to rotate the sleeve and gear wheel is transmitted from any suitable motor which, in the operation of the device, is designed to run continuously. Adjacent to the end of sleeve 7 there is rigidly fixed to the shaft 4, a sleeve 8, from which project, at substantially right angles, two arms 9 and 10. In one of said arms, as 9, near its end is journaled a short shaft 11 carrying at one end a pinion 12 that engages with a gear wheel 13 fixed to sleeve 7, and at the other end a ratchet wheel 14. To the other arm 10 and near its base is pivoted a bell crank lever 15 connected by a spiral spring 16 to the arm 9 and operating under the influence of said spring as a pawl for the ratchet wheel 14, to lock the sleeve 7 to the shaft, when in engagement therewith. Into the path of the free end or arm of the pawl 15, projects through a standard 17, a slide rod 18, pivotally connected to the upper end of a lever 19 which extends through a slot in the base plate 1 and is pivoted to a stud 20 fixed to said plate. A spiral spring 23 connected to lever 19 and to the standard 17, maintains the end of the rod 18 normally across the path of end of pawl 15. When, therefore, by the rotation of the shaft these two parts are brought forcibly into engagement, the pawl is lifted from the teeth of the ratchet, leaving the sleeve 7 free to revolve upon the shaft 4. A notched cam disk 21 upon which slides a spring pawl 22 is fixed to shaft 4 in such position that coincidentally with the release of pawl 15, the pawl 22 slips into the notch and locks the shaft against backward movement. Beneath the base plate 1 is secured an electromagnet 24, having an arm 25 extending from its armature and which, when the magnet is energized engages the lower projecting end of the lever 19 and withdraws the end of the slide rod 18 from engagement with the pawl 15. This operation reestablishes connection between the sleeve 7 and shaft 4, which continues until the pawl 15 again encounters the rod 18. As the spring 16 is under slight tension at the instant of engagement of the pawl 22 with the notch in cam disk 21 even an instantaneous withdrawal of the rod 18 releases the pawl and allows it to rotate sufficiently to prevent the return of the rod 18 to its forward position until after the pawl has passed beyond it. To insure the proper operation of these parts and to cushion the impact between the arm of pawl 15 and the slide rod 18, which results from the rapid rotation of the shaft 4, the standard 17 is mounted at the end of

a plate or bar 31 pivoted at the other end to lugs on the base plate 1 and carrying a rod 32 that extends downward through the plate 1, between which and a head on the lower end of said rod is a spiral spring 33. To the right hand end of the shaft 4 which projects beyond its bearing in standard 3, a split brass sleeve 25 integral with a contact disk is secured by a strap 27. The outer side of the disk 26 is faced with vulcanite and carries a contact arm 28 in electrical connection with the sleeve and disk, the end of which arm is arranged to sweep over a stationary sunflower ring 29, composed of alternate insulating and conducting segments and rigidly mounted on a standard 30. At the receiving end of the line an instrument is used which is or may be, in the particulars above enumerated and described, of identically the same construction as that at the sending end. This instrument is illustrated in Fig. 10, and the parts corresponding to those which have been described in connection with the sending device are indicated by the same reference numerals, but to each of which is affixed the exponent "a". Those details of construction which distinguish the two instruments will be pointed out in connection with the description of operation.

In the practical operation of systems of this kind local receiving as well as transmitting instruments, as is well known are always used, and the impulses are relayed instead of being sent directly to line. As these, however, have to do with the working of the system and not with the particular functions of the apparatus in which my invention resides and are all well understood by those skilled in the art, I shall omit, for purposes of illustration, all such devices and assume that the current impulses are sent directly to line through the sunflower circuits and a contact spring or brush 34 bearing against the conducting side of the disk 26 of the transmitting sunflower, and are received directly from line by the corresponding brush 34a in the receiving sunflower.

To adapt the instrument to such uses as above indicated, it is provided with a number of terminals, placed most conveniently on the base plate in the rear of the working parts, and of which those indicated by the letters A to K inclusive, are designed for connection with circuits from a keyboard, whose office it is to control the operation of the device and to set up the combinations of contacts that result in the transmission of the impulses that constitute signals according to a prearranged code.

The transmitting sunflower ring contains eight conducting segments numbered 47 to 54, inclusive, and its arm 28 bears normally on segment 47, connected to terminal H.

This particular circuit, however, is used for the special purpose of operating a polarized relay and may be left out of present consideration the segment 47 being regarded as a blank, as is also the corresponding segment 47^a in the receiving sunflower. Let it be assumed that the keyboard or any other suitable device is operated to send one or more impulses constituting a signal corresponding to a given character. The first result of such operation must always be to send through the circuit of terminal J to ground, a momentary current impulse that energizes the magnet 24 and releases the shaft 4 which, assuming the sleeve 7 to be in continuous rotation, instantly starts and makes one complete revolution. Let it be further assumed that by the same operation of the keyboard, battery is always connected at once to terminal G. The path from this terminal will be seen to lead to segment 48 and hence an impulse will be sent to this segment, brush 28 and brush 34 to line. The normal position of the receiving sunflower, as indicated by the diagram, is that in which its rotating arm 28^a rests upon segment 48^a, so that the first impulse received by its brush 34^a will be through that segment and hence through the shaft releasing magnet 24^a to ground. The receiving sunflower will thus be started, and its shaft permitted to make one revolution. Let it be further assumed that by the same operation of the keyboard, battery is connected to one or more of the terminals, say, that numbered B, which is connected to segment 50, and E, which is connected to segment 53. From this it will result that a current impulse will be sent to line during the passage of the brush 28 over each of these segments and will be received by the distant sunflower over corresponding segments which are designed to be connected through terminals p, q, r, s, t and u, to the line controlled circuits of the translator, to which reference has been made above. Thus according to the battery connections established by the keyboard to terminals A, B, C, D, E, F and G, signals or groups of impulses corresponding thereto, will be sent to line and distributed through the corresponding circuits of the receiving sunflower, and as both of said instruments are started and stopped at the unison point for each complete signal, the synchronizing of the instruments is greatly simplified. In fact, their respective speeds may manifestly differ to a considerable extent without interfering with their correct coöperative performance.

In the particular system for which the above described instruments are designed, current impulses sent through segments 49, 50, 51, 52 and 53 and received through the corresponding segments of the receiving sunflower, are intended to operate the sealing

magnets of the translator and those through segments 54 and 54^a a magnet in the translator that effects, through the control of suitable mechanism, a shifting of the type-wheel of the printing mechanism through one character space. By means of the devices thus far described, however, those operations only which are involved in the establishment of the desired permutations and combinations in the controlling mechanism are performed. It remains, therefore, to describe those devices which render these combinations effective in bringing about their intended result.

On shaft 4 of the sending sunflower, see Figs. 1 and 3, is mounted a cam disk 55 against the edge of which bears a spring actuated lever 56, provided at its end with an anti-friction roller 57. The lever 56 carries a contact spring 58, which at a given point in the rotation of the shaft 4 is forced into contact with a stop 59 to complete a circuit. The counterpart of this device is present in the receiving sunflower as shown in Fig. 9, and in the latter it operates to close the circuit from a battery 60, representing any local source of current, through wire 61 to terminal v which is designed to be extended through the circuit including the release or main operating magnet of the translator. The high point of the cam 55^a does not encounter the lever 56 until after the shaft 4^a has so far completed a revolution that all of the segments of the sunflower have done their work and the desired adjustment of the translator has been established thereby. In the transmitting instrument the same circuit controller in the same relation to the sunflower ring is used for the purpose of operating the release magnet 101 of the local translator for which purpose it is shown as controlling a circuit from any available source of current 62 to a terminal L, from which the proper connection to the local translator may be established. On the shaft of the sending sunflower instrument there is also a cam disk 64 that operates a circuit closer 65 controlling a circuit from the battery 62 to terminal I. The cam is of such shape and so secured to the shaft 4 that it will be operated to close this circuit immediately after the shaft has started in rotation and is designed to control the action of the keyboard or its equivalent, by locking, through the instrumentality of an electro magnet, the depressed key down and the other keys up, until the shaft 4 has practically completed one full revolution. This mutual control of the two instruments prevents an operator from sending one signal before another has been completed.

There is a third circuit closer in the sending instrument which may comprise a cam disk and circuit controller lever of the same construction and mode of operation as those

- just described, but which, in the drawings, see Figs. 1 and 7, is shown as comprising a cam disk 66 secured to the end of shaft 4 and a spring actuated contact lever 67 bearing thereon and pivoted to an insulating plate 68, secured to base plate 1. When this lever 67 is depressed by the cam it is forced into engagement with a spring contact 69 to complete a circuit from battery 62 to terminal K.
- 5 10 The said terminal is connected with a circuit in the keyboard instrument which is designed to include an electromagnet that must operate before current can be sent through the contacts selected by the depression of 15 any given key. This arrangement is not illustrated herein as it forms no part of the present invention, but is referred to in illustration of the feature of the instrument which is subject of the present application 20 and which consists in the combination of circuits from the keyboard to the sunflower and circuits from the sunflower to the keyboard and through the instrumentality of which the mutual control of the two instruments is 25 effected. In other words as has been described above the keyboard starts the sunflower in operation and the latter thereupon establishes conditions in the keyboard which permit it to exercise its allotted functions 30 and prevent it from effecting any other operation until these have been completed.
- In certain obvious respects the invention as hereinbefore described, is not limited to the details of construction and arrangement 35 adopted for convenience or illustration. For example, in sunflower instruments of the general character described, it is possible to rotate either the brushes or the contact rings, and it is usual, for this reason, 40 to refer to the operations of such instruments as revolutions of the sunflower. The most characteristic feature of the improvement, however, is that the two sunflower instruments shall start from rest and complete 45 one revolution or cycle of operations in substantial synchronism for each signal transmitted, the release of one being effected by a current impulse transmitted by the initial movement of the other.
- 50 What I claim is:—
1. A transmitting apparatus for printing telegraph systems, comprising in combination the following elements; sunflower instruments with corresponding contact segments and at opposite ends of a line; means for operating the same which are normally locked; circuits in both instruments and releasing means operated thereby for permitting the shafts to make one revolution, the 55 releasing circuit of the sending instrument being a keyboard controlled circuit independent of the sunflower circuits and that in the receiving instrument being connected with the first contact segment to receive current from line.

2. A transmitting apparatus for printing telegraph systems, comprising in combination, two normally locked sunflower instruments having corresponding contact segments and located at opposite ends of a line; means for releasing the sending sunflower and means for releasing the receiving sunflower, and a circuit including the last named releasing means directly connected with that contact segment of the receiving sunflower which is first to receive current transmitted by the initial movement of the sending sunflower on the release and operation of the same.

3. A transmitting apparatus for printing telegraph systems, comprising in combination, two normally locked sunflower instruments having corresponding segments and at opposite ends of a line, means for releasing the sending instrument to make one revolution, and electrically controlled means for the same purpose in the receiving instrument, and a circuit, including said releasing means, connected directly with that contact segment which is first to receive current transmitted by the initial movement of the sending sunflower on the release and operation of the same.

4. In a transmitting instrument for printing telegraph systems, the combination with the sunflower ring and rotatable shaft of the sending apparatus, of a series of keyboard controlled circuits one for starting the sunflower in operation and the others connected to sunflower segments for sending impulses to line, keyboard controlling circuits and circuit controllers therein adapted to be operated by the movement of the sunflower shaft.

5. In a transmitting instrument for printing telegraph systems, the combination with the sunflower ring and rotatable shaft of the sending apparatus, of a series of keyboard controlled circuits connected with the sunflower segments, a keyboard controlled circuit and a releasing device for the sunflower operated thereby, keyboard controlling circuits and circuit controllers therein, and cams on the shaft of the sunflower for operating said circuit controllers.

6. The combination with a rotatable shaft and a power driven sleeve, of means for locking the sleeve to the shaft and releasing it therefrom, consisting of a pinion and a ratchet wheel on a spindle carried by the shaft and eccentric thereto, the said pinion meshing the sleeve, a spring actuated pawl also carried by the shaft and adapted to engage with the ratchet, a movable stop in the path of the pawl and means for preventing backward movement of the shaft from its point of release.

7. The combination with a rotatable shaft and a power driven sleeve loose thereon, of means for locking the sleeve to, and releas-

ifing it from the shaft, consisting of a pinion and ratchet wheel on a spindle carried by the shaft and eccentric thereto, the said pinion meshing with the sleeve, a spring actuated pawl also carried by the shaft and adapted to engage with the ratchet, a spring seated stop in the path of the pawl, means for withdrawing said stop to permit the shaft to make one revolution and means for preventing backward movement of the shaft from its point of release.

In testimony whereof I affix my signature in the presence of two subscribing witnesses.

JOHN EDWARD WRIGHT.
